CLAIM

The ornamental design for pouch for oral use, as shown and described.

DESCRIPTION

FIG. 1 is a perspective view of a pouch for oral use showing a first embodiment of my new design;

FIG. 2 is a cross sectional view thereof, taken in a plane perpendicular to a longitudinal dimension of the pouch for oral use;

FIG. 3 is a top plan view thereof;

FIG. 4 is a left side elevational view thereof;

FIG. 5 is a rear elevational view thereof;

FIG. 6 is a bottom plan view thereof;

FIG. 7 is a right side elevational view thereof;

FIG. 8 is a front elevational view thereof;

FIG. 9 is a perspective view of a pouch for oral use showing a second embodiment of my new design;

FIG. 10 is a cross sectional view thereof, taken in a plane perpendicular to a longitudinal dimension of the pouch for oral use;

FIG. 11 is a top plan view thereof;

FIG. 12 is a left side elevational view thereof;

FIG. 13 is a rear elevational view thereof;

FIG. 14 is a bottom plan view thereof;

FIG. 15 is a right side elevational view thereof;

FIG. 16 is a front elevational view thereof;

FIG. 17 is a perspective view of a pouch for oral use showing a third embodiment of my new design;

FIG. 18 is a cross sectional view thereof, taken in a plane perpendicular to a longitudinal dimension of the pouch for oral use;

FIG. 19 is a top plan view thereof;

FIG. 20 is a front elevational view thereof;

FIG. 21 is a rear elevational view thereof;

FIG. 22 is a left side elevational view thereof;

FIG. 23 is a bottom plan view thereof;

FIG. 24 is a right side elevational view thereof;

(Continued)

FIG. 25 is a perspective view of a pouch for oral use showing a fourth embodiment of my new design;
 FIG. 26 is a cross sectional view thereof, taken in a plane perpendicular to a longitudinal dimension of the pouch for oral use;
 FIG. 27 is a top plan view thereof;
 FIG. 28 is a left side elevational view thereof;
 FIG. 29 is a rear elevational view thereof;
 FIG. 30 is a bottom plan view thereof;
 FIG. 31 is a right side elevational view thereof;
 FIG. 32 is a front elevational view thereof;
 FIG. 33 is a perspective view of a pouch for oral use showing a fifth embodiment of my new design;
 FIG. 34 is a cross sectional view thereof, taken in a plane perpendicular to a longitudinal dimension of the pouch for oral use;
 FIG. 35 is a top plan view thereof;
 FIG. 36 is a left side elevational view thereof;
 FIG. 37 is a rear elevational view thereof;
 FIG. 38 is a bottom plan view thereof
 FIG. 39 is a right side elevational view thereof; and,
 FIG. 40 is a front elevational view thereof.
 The evenly spaced broken lines in the drawings illustrate portions of the pouch for oral use that form no part of the claimed design.
